UNITED STATES PATENT OFFICE.

KUNISUKE SUYEHIRO, OF SALT LAKE CITY, UTAH.

GIFT-COUPON.

1,250,706.

Specification of Letters Patent. Patented Dec. 18, 1917.

Application filed January 26, 1917. Serial No. 144,705.

To all whom it may concern:

Be it known that I, KUNISUKE SUYEHIRO, a citizen of the United States, residing at Salt Lake City, in the county of Salt Lake 5 and State of Utah, have invented a new and useful Gift-Coupon, of which the following is a specification.

This invention has reference to gift coupons and its object is to provide a coupon 10 accompanying or forming part of a carrier in the form of a book, leaflet, card or the like, displaying views of and describing various articles from which a choice may be made and which will be furnished on the presentation of the coupon or certificate.

Difficulty is often experienced at Christmas and at other times when it is desired to send a gift to some one, to choose an appropriate gift which will not only be useful 20 but acceptable to the recipient. The invention provides a means whereby the recipient is enabled to have considerable latitude in choosing a gift and the sender is relieved from the embarrassment of making the choice 25 with the possibility of such choice being unsatisfactory to the recipient, or perhaps duplicating some other gift.

The invention comprises a certificate accompanied by a descriptive list of articles 30 from which choice may be made, and with the assurance that on sending or presenting the certificate to the proper dealer the chosen article will be delivered, the choice 35 being left to the recipient and the sender being freed from making a choice further than to determine the cost of the article.

The arrangement is such that the certificates may be sold by retailers to customers desiring to make the gift, whereupon the 40 certificate is properly authenticated by the retailer to be then honored by the dealer furnishing the goods on presentation of the certificate. By appropriate designations the price of the goods need not appear upon the 45 list accompanying the certificate or upon the certificate itself, and the goods may be designated solely by indicia. By means of the invention a gift may be made by certificate by means of which the recipient may obtain 50 any desired one of a large variety of articles, and thus not only have the pleasure of the gift, but the pleasure of a gift satisfactory to the recipient.

The invention will be best understood from 55 a consideration of the following detailed

description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:

Fig. 1 is a face or cover view of the book form of gift coupon;

Fig. 2 is a view of the book of Fig. 1 opened out to show the coupon or certificate;

Fig. 3 is a view of the book of Fig. 1 opened out at another place to show a list of articles by name, number, description and illustration.

Fig. 4 is an opened out folder form of 75 coupon showing the list of articles to be obtained.

Fig. 5 is a view similar to Fig. 4, but with the article list turned back to display the 80 coupon.

Fig. 6 is a view of the portion of the folder shown in Fig. 5 but seen from the outer face to indicate the address portion occurring on the opposite face of the coupon shown in Fig. 5.

Fig. 7 is a view of the folder of Fig. 4 in the folded condition, ready for mailing.

Figs. 8 and 9 are opposite face views of a mailing card with an envelop form of coupon holder.

Fig. 10 is a view of the envelop coupon holder of Fig. 8 opened out to show the interior thereof.

Fig. 11 is a view of the envelop coupon holder in the folded condition.

Fig. 12 is a face view of a postal card form of coupon.

Fig. 13 is a view of the card of Fig. 12 as seen from the opposite face.

In accordance with the present invention 100 there is provided a gift coupon printed in an attractive form. In the book arrangement shown in Fig. 1 and associated figures, there is a coupon 1 printed on one of the leaves of the book with a line 2 either perforated or otherwise arranged whereby the coupon may be readily removed from the book. Printed on the coupon is a legend 3 indicating the purpose of the coupon for Christmas or other presents, as may be desired. For identifica- 105

tion and other purposes the coupon is provided with a number, indicated at 4, with a space 5 for the name of the firm to supply the articles, another space 6 for a catalogue number, and other spaces 7 for the name and address of the person sending the coupon for redemption or for verification.

In the arrangement of Fig. 1 and associated figures the book form of coupon has 10 a cover member 8 with a space 9 for greetings to the person to whom the coupon is to be sent, and another space 10 for the name of the sender, the book cover being printed or otherwise ornamented to any desired 15 extent.

In order to show to the recipient what choice may be made of various articles, the book is provided with leaves 11, 12, containing lists 13 of articles, catalogue numbers 14, 20 descriptive matter 15 and illustrations 16.

Each coupon has a designation 17 indicating to the dealer and seller the value of the coupon. A simple form of designation may be a letter of the alphabet, in which 25 case the letter A would designate the lowest value of coupon, say, twenty-five cents, the letter B would indicate a higher value, say, fifty cents, and so on.

In Fig. 4 and associated figures there is 30 shown a folder 18 inclosing a list 19 corresponding to the lists 11 to 16 of Fig. 3. The folder is provided with a gummed flap 20 with gummed tabs 21 and that portion of the folder, which is divided into sections, visible on the face remote from the folder when the latter is sealed up for mailing, as shown in Fig. 7, has a space 22 for a postoffice address, and on the face of the same section remote from the address space 22 there is 35 40 printed a coupon 23 with lines 24 outlining the coupon and indicating where the coupon is to be severed from the folder. This coupon may be normally covered by the price list 19, which latter must be lifted from 45 covering relation to the coupon after the folder is open in order to disclose the coupon.

When it is desired to send a folder such as shown in Fig. 4 and associated figures, it is 50 folded up into the form indicated in Fig. 7 and sealed and addressed, and may then be sent by mail in the usual way. The recipient has but to cut through the flap 20, whereupon the folder may be opened and 55 the coupon filled out as described with respect to Fig. 2.

Still another arrangement is indicated in Figs. 8 to 11, where a card 25 is formed along one edge with a return flap 26, and 60 secured by stitching 27 or in any other suitable way to the card is an envelop 28 in the form of a folder, this envelop having a gummed flap 29 and gummed side flaps 30, and on the side of the body of the envelop indicated at 31 remote from the flap 29 are

continuations 32 upon which may be printed a list of articles and description thereof similar to the arrangement shown in Fig. 3.

The envelop 28 has an address receiving portion 33 and on the inner face of the body 70 31 of the envelop there is produced a coupon 34.

The card 25 is utilized as a carrier for the envelop and may be of a size to permit its inclosure in an ordinary letter size envelop, 75 or may be even addressed and stamped and mailed after the manner of a postal card. The envelop 28 may be sent to the person to whom the gift is to be made in the sealed condition, or it may be sent in the open condition. If sent sealed then the envelop must be opened in the usual manner, whereupon the coupon 34 is cut out along designating lines 35, but if the envelop is sent unsealed then the recipient may use the envelop as a 80 carrier for mailing the coupon to the concern which is to furnish the goods. Of course, the envelop 28 may be furnished without the card 25, and in such case it is sealed, addressed and mailed to the party 90 to whom the gift is to be made, and the recipient then removes the coupon and sends it properly filled out to the dealer.

In Fig. 12 there is shown a simple coupon in the form of a postal card 36 having the 95 usual address section 37, correspondence section 38 and space 39 for the address of the sender. The other face of the postal card is provided with a coupon 40 and a list 41 of articles similar to the lists shown in Fig. 3, 100 but necessarily less comprehensive on account of limited space.

A seller of the coupons can well afford to furnish them at face value, since there is no necessity of carrying any stock of goods, 105 for the seller may merely act as a distributor receiving a certain percentage for services. The dealer honoring the coupons can readily obtain larger profits than would be obtainable from furnishing the goods at 110 wholesale rates.

If the certificates be of an elaborate nature, then a small amount may be charged for them over and above their face value.

The recipient is enabled from a wide 115 choice afforded to obtain an article representing not only the thoughtfulness of the sender, but insuring additional satisfaction in enabling the recipient to obtain a desired article.

In all forms of the invention there is provided a coupon or certificate with means for transmitting it, usually by mail, to the person intended, and so arranged that the coupon may be readily removed and forwarded by the recipient to the dealer or concern furnishing the goods on presentation of the certificate. Accompanying each certificate is a descriptive list of a variety of goods any article of which is furnished on 130

presentation of the certificate, the list being sufficiently complete in description and showing to enable the recipient to readily make a satisfactory choice.

5 When the space for receiving the sending address coincides with the space for the coupon on the opposite side of the sheet intended to receive the sending address, then it is unnecessary to fill in the name of the 10 recipient on the coupon, since such name already appears within the address space.

What is claimed is:—

1. A gift coupon provided with a descriptive list of articles for any one of which the 15 coupon will be accepted, said list forming a component part of the coupon, and said coupon also being provided with arbitrary indicia secretly designating its value.

2. A gift coupon structure provided with 20 appropriately designated spaces for receiv-

ing the name of the sender and the name and address of the recipient, a space for designating a chosen article, and arbitrary indicia secretly representing the value of the coupon for designated articles. 25

3. A gift coupon provided with an illustrated list of articles for one of which the coupon will be honored, and having each article accompanied by indicia for indicating upon the coupon the desired article, and said coupon having indicia arbitrarily and secretly indicating its value. 30

In testimony that I claim the foregoing as my own I have hereto affixed my signature in the presence of two witnesses.

KUNISUKE SUYEHIRO.
